FIRING MECHANISM FOR A SALVO GUN

David C. Fletcher, Springfield, Mass., assignor to the United States of America as represented by the Secretary of the Army

Filed Nov. 9, 1956, Ser. No. 621,486

9 Claims. (Cl. 89—127)

(Granted under Title 35, U.S. Code (1952), sec. 266)

The invention described herein may be manufactured and used by or for the Government for governmental purposes without the payment of any royalty thereon.

This invention relates to firearms and more particularly to the firing mechanism therefor.

It is an object of this invention to provide for salvo rifles having a plurality of barrels a mechanism for firing all the barrels simultaneously.

It is another object of this invention to provide for salvo rifles having a plurality of barrels a semiautomatic mechanism whereby all the barrels are fired simultaneously each time the trigger is pulled.

It is a further object of this invention to provide for salvo rifles having a plurality of barrels and a bolt having breech closure portions with a firing pin for each of the barrels a firing mechanism including strikers for actuating the firing pins simultaneously when the bolt is locked in battery position.

It is a still further object of this invention to provide for salvo rifles having a plurality of barrels a firing mechanism wherein the strikers which are actuatable against the firing pins for firing the cartridges in the barrel chambers are cocked simultaneously by a rotary sear and are released together by a trigger.

It is still another and further object of this invention to provide for salvo rifles having a plurality of barrels a firing mechanism having a rotary sear and an actuator for converting pivotal movement of a trigger to rotary movement of the sear.

It is another and still further object of this invention to provide for the firing mechanism of a salvo rifle a safety device to prevent actuation of the trigger before the rifle is in battery.

The specific nature of the invention as well as other objects and advantages thereof will clearly appear from a description of a preferred embodiment as shown in the accompanying drawings in which:

Fig. 1 is a longitudinal cross-sectioned view of a salvo rifle embodying the firing mechanism of this invention showing the strikers releasably held in cocked position by the sear;

Fig. 2 is a view similar to Fig. 1 but showing the strikers released to actuate the firing pins for firing the chambered cartridge;

Fig. 3 is a view taken along line 3—3 of Fig. 1;

Fig. 4 is a view taken along line 4—4 of Fig. 2;

Fig. 5 is a view similar to Figs. 1 and 2 but showing the trigger held rearwardly by the safety member;

Fig. 6 is a view taken along line 6—6 of Fig. 5;

Fig. 7 is a view taken along line 7—7 of Fig. 1;

Fig. 8 is a perspective exploded view of the trigger mechanism; and

Fig. 9 is a perspective exploded view of the striker and sear mechanisms.

Shown in the figures is a rifle having a tubular receiver 12 with three barrels 14 mounted to the front end thereof, and a gas-actuated operating rod 16 mounted axially through the receiver for longitudinal reciprocation be-

tween a rearward and a forward position. A feed rotor 18 is rotatably mounted in the front end of receiver 12 adjacent the breech ends of the barrels 14, and such feed rotor is provided with three channellike secondary chambers 20 which receive cartridges from a magazine 22 and simultaneously align a cartridge with each one of the barrels. Feed rotor 18 is rotated to load the secondary chambers 20 by means of the slidable engagement of three pin followers 24 mounted in such feed rotor with a set of three cam grooves 26 generated along operating rod 16.

The cartridges in the secondary chambers 20 are moved into the chambers of the barrels 14 and removed therefrom after being fired by a bolt 28 having a hub portion 30, which is slidable in an axial bore 32 provided in said rotor 18, and three breech closure portions 34, which extend radially from the hub portion to be slidably received by the secondary chambers. Each of the breech closure portions 34 is provided with an integral extractor portion 36, which is received by the extractor grooves of the cartridges when they enter the secondary chambers 20 from magazine 22, and a slidable firing pin 38, which is actuatable against a chambered cartridge. The breech closure portions 34 are receivable in a cylindrical cavity 40 which is formed in the front end of said rotor 18 by an annular flange 41 when bolt 28 is in battery. Whereby, such feed rotor may be rotated by the cam grooves 26 and pin followers 24 to move the secondary chambers 20 some 47 degrees out of alignment with the breech closure portion 34 in a direction counter to that in which the feed rotor is rotated during the preceding feeding cycle to block the bolt against rearward movement. Bolt 28 is movable between a retracted and a battery position by the engagement of lugs 42 on operating rod 16 with the bolt during reciprocation of the operating rod.

The device for actuating the firing pins 38 to fire the three barrels 14 simultaneously includes three strikers 44 which are slidably mounted in feed rotor 18 so that each is aligned with one of the firing pins 38 when such feed rotor is rotated to bolt locking position and which are actuatable against such firing pin as hereinafter explained. Also, a cocking ring 46 which cocks the three strikers 44 simultaneously during rotation of feed rotor 18 to unload and load the secondary chambers 20, a ring-like sear 48 for releasably holding the strikers in cocked positions, a rotatable sear release 50 for cammingly rotating the sear to release the strikers, a pivotal trigger and a rectangular actuator 52 which is angularly displaced along the length of the front portion thereof to form a screw which cooperates with the sear release for converting the pivotal movement of a trigger 53 to rotatable movement of the sear release.

The strikers 44 are cylindrical rods which are slidably mounted in mating holes provided longitudinally in said rotor 18 and which are so disposed therein that each is engageable with one of the firing pins 38 as has hereinbefore been explained. Such holes include a bore 56 and a counterbore 58 which is introduced from the rear end of feed rotor 18 to form an annular shoulder 60. Each of the strikers 44 includes a head portion 62 which is slidably mounted in the bore 56 for engagement with respective ones of the firing pins 38, an annular collar portion 64 which slidably mounts the front end of the striker and limits the forward position thereof by the engagement with shoulder 60, and a body portion 66. The rear end of each of the strikers 44 is slidably supported by a sleeve 68 which is locked in place in one of the counterbores 58 by a bayonet lug 70. Mounted on each of the body portions 66 is a compressible coil spring 72 which engages the rear side of the collar portion 64 and the front end of the sleeve 68 to bias the striker 44 forwardly to the firing pin striking position,

Provided on each of the strikers 44 adjacent the rear end thereof is a first chordal flat 74, which forms a segmental engaging portion 75 at the rear end thereof, and a second chordal flat 76 which extends forwardly therefrom. Second chordal flats 76 are cut deeper than first chordal flat 74 so as to form a ledge portion 78 at the junctions therewith. The rear portion of said rotor 18 is reduced in diameter, as noted at 80, so that the rear portions of strikers 44 are exposed and so that the periphery is aligned with the second chordal flats 76. Such reduced portion 80 is terminated by an annular shoulder 82 at the forward end thereof.

Mounted in receiver 12 rearwardly of feed rotor 18 is a cuplike housing 84 which is disposed in the receiver so that the base thereof is directly above trigger 53 and the rim is spaced slightly rearward of shoulder 82 to provide space so that sear 48 can be rotatably retained therebetween. An axial bore 86 through the base of housing 84 permits passage of operating rod 16. The inner diameter of sear 48 is approximately that of reduced diameter portion 80 whereby the rear side of sear 48 is engageable by the ledge portions 78, and such sear and such ledge portions are so related that when in engagement, the strikers 44 are in cocked positions. Extending into sear 48 from the inside diameter thereof are three semicylindrical notches 90 which are alignable during rotation of the sear with the strikers 44 to free the ledge portions simultaneously and permit the strikers to be moved forwardly by the biases of springs 72 for simultaneous contact with the firing pins 38.

Sear 48 is limited in rotation between a striker release position, wherein the notches 90 align with strikers 44 for release therefrom, and a holding position, wherein the ledge portions 78 are engaged by the sear to releasably hold the strikers in the cocked position by a tang 92 which extends from the inside diameter of the sear to be slidily received in a slot 94 provided in reduced diameter portion 80. A compressible coil spring 96 is mounted in slot 94 against tang 92 for biasing sear 48 to the holding position.

The outside diameter of cocking ring 46 is approximately the same as the inside diameter of housing 84 so as to be received for rotatable and slidable movement therein. Clearance cuts 99 are provided in cocking ring 46 to permit the passage of the rear portions of the strikers 44 and to connect such cocking ring to the feed rotor 18 for rotation therewith through engagement with such strikers. The engaging portions 75 are engaged with the rear side of cocking ring 46 above clearance cuts 99 whereby rearward movement of such cocking ring retracts the three strikers 44 simultaneously. Spaced equally around the outside periphery of cocking ring 46 are four follower lugs 98 which are slidable in mating cam tracks 100 provided in housing 84. The cam tracks 100 are so generated that during rotation of cocking ring 46, when feed rotor 18 is rotated to unload and load the secondary chambers 20, such cocking ring is moved sufficiently to retract the strikers 44 to their cocked positions.

As has been hereinbefore stated, sear 48 is rotated to release the strikers 44 by sear release 50. Such sear release includes a cylindrical shank portion 102 and a head portion 104 with a tooth portion 106 extending radially therefrom. Shank portion 102 is slidily and rotatably mounted in a trigger housing 108 which in turn is mounted within receiver 12 immediately below housing 84 so that tooth portion 106 is received in a recess 110 provided in the rear face of sear 48 adjacent the periphery thereof. Recess 110 is substantially triangular in configuration with an angular side 111 leading from the rear side of sear 48 and a base portion 112. Whereby, when sear release 50 is rotated, tooth portion 106 moves against base portion 112 to rotate sear 48 sufficiently to align the notches 90 in sear 48 with the strikers 44 for release thereof.

As sear 48 rotates with feed rotor 18 and as such feed rotor, after the rifle is fired, is rotated first to unlock bolt 48 and then counterrotated to unload and load the secondary chambers 20, a cam portion 113 is provided on tooth portion 106 so as to be engageable with angular side 111 of recess 110, during rotation of the feed rotor to unlock the bolt, for camming sear release 50 rearwardly in trigger housing 108.

Sear release 50 is releasably held in the rearward position, so as to be out of the way of sear 48 when counterrotated with feed rotor 18, by a latch member 114. Such latch member 114 includes a body portion 116, which is intermediately mounted on a transverse pin 118 for pivotal movement between a latch and an unlatch position, and a lip portion 120, which extends upwardly to catch in back of sear release 50 when cammed to the rearward position. Latch member 114 is biased to the latch position by a leaf spring 122. When sear release 50 is in the forward position, latch member 114 is held in unlatch position by the engagement of lip portion 120 with head portion 104 of the sear release. Such latch member 114 is pivoted to release sear release 50 by trigger 53 through means hereinafter explained.

Trigger 53 is mounted for pivotal movement in trigger housing 108 directly rearward of latch member 114 on a transverse pin 124, and such trigger is provided with a shelf portion 126 which is engageable with the underside of the rear portion of latch member 114 and which, when such trigger is in normal forward position, pivots such latch member to unlatch sear release 50. Trigger 53 is also provided with an extension portion 128 which extends upwardly above pin 124 for cooperation with actuator 52 as hereinafter explained.

Actuator 52, as has been stated, is rectangular in configuration and has a square cross-section which is angularly displaced approximately 45° along the length of the forward portion thereof. The front end of actuator 52, where angularly displaced, is slidily received by an axial cylindrical hole 130 in shank portion 102 of sear release 50 and a vertical slot 134 through the rear portion of actuator 52 receives the upper end of extension portion 128. The rear end of hole 130 is provided with a square orifice 132 which has approximately the same dimension as actuator 52. Whereby, when trigger 53 is actuated to fire the rifle, actuator 52 is moved forwardly and because of the twist along the length thereof and the sliding cooperation thereof with orifice 132, sear release 50 is rotated against sear 48 for actuation thereof to release the strikers 44. A compressible coil spring 135 is mounted on actuator 52 and seats against the rear end of shank portion 102 of sear release 50 and the front side of extension portion 128 of trigger 53 to bias such trigger to normal forward position and such sear release forwardly into resilient engagement with sear 48.

Provided on operating rod 16 rearwardly of housing 84 is a collar 136 which provides the front abutment for an operating rod spring 138 mounted on such operating rod whereby the operating rod is returned to normal forward position after being actuated rearwardly responsive to the firing of the rifle. Extending forwardly from collar 136 is a pair of diametrically-opposed prong portions 140 which lie in the vertical plane of the rifle and which are tapered inwardly towards the front. Such prong portions 140 are receivable through bore 86 in the base of housing 84 when operating rod 16 is in normal forward position.

Provided in the base of housing 84 is a vertically-disposed T-slot 142 which is terminated at the upper end by a top side 144 and which slidily receives a safety member 146. An elongated hole 150 through safety member 146 permits the passage of operating rod 16 therethrough and the prong portions 140 when said operating rod is in full forward position. Extending downwardly from the bottom side of safety member 146 is a tab portion 152 which engages the top of extension portion 128

of trigger 53 when such trigger is in normal forward position and which is slidable in back of such extension portion when such trigger is in the retracted position to block the return of the trigger to normal forward position. A cam block 154 is mounted to the rear face of safety member 146 above hole 150 to be engageable with the top one of the prong portions 140; when operating rod 16 approaches full forward position, so that such safety member is cammed upwardly to free trigger 53 when such operating rod is in full forward position. A compressible coil spring 156 is mounted between the top of safety member 146 and the top side of opening 86 to bias such safety member downwardly to block trigger 53.

Operation

Thus, when the firearm is in battery and ready to be fired, operating rod 16 is in normal forward position with the upper one of the prong portions 140 holding safety member 146 upwardly so that trigger 53, unblocked by tab portion 152, is in normal forward position. Bolt 28 is in the battery position with the breech closure portions 34 closing the breeches of the barrels 14 in back of the chambered cartridges and is locked in battery position by feed rotor 18 being rotated by the cam grooves 26 to lock position. With feed rotor 18 in lock position, the strikers 44 are aligned with their respective firing pins 38.

To fire the rifle, trigger 53 is pulled rearwardly whereby, actuator 52 is moved forwardly in sear release 50 to cause rotation thereof through the cooperation of the angular twist along the actuator and the mating orifice 132 in the sear release. As sear release 50 is rotated, tooth portion 106 moves against wall 112 of recess 110 to cammingly rotate sear 48 so that the notches 90 are rotated into alignment with the strikers 44. When the notches 90 come into alignment therewith, the strikers 44 will be released to strike the firing pins 38 simultaneously and fire the cartridges in the three barrels 14 together.

Operating rod 16 is moved rearwardly responsive to the firing of the rifle and during the initial portion of such rearward movement, the prong portions 140 are moved away from safety member 146 permitting spring 156 to bias such safety member downwardly so that tab portion 152 moves in back of extension portion 128 which was moved forwardly when trigger 53 was pulled to fire the rifle. Consequently, trigger 53 is safetied against actuation again until operating rod 16 returns to normal forward position which insures that the trigger cannot be actuated to release the strikers 44 before the rifle is in battery and thereby requires recharging. Also, during the initial portion of the rearward movement of operating rod 16, the cam grooves 26 thereon cause rotation of feed rotor 18 to align the secondary chambers 20 with their respective breech closure portions 34 and so unlock bolt 28. As feed rotor 18 is rotated, sear 48 is rotated therewith and during such rotation, sear release 50 is cammed rearwardly by the cooperation of angular side 111 with cam portion 113 until lip portion 120 of latch member 114 is moved upwardly by spring 122 in back of head portion 104. Whereby, sear release 50 is releasably held out of the way during counterrotation of sear 48 when feed rotor 18 is counterrotated to unload and load the secondary chambers 20 during the continued rearward movement of operating rod 16.

During such unloading and loading portion of the operating cycle, cocking ring 46 is moved rotatably rearward in housing 84 by means of the follower lugs 98 on such cocking ring and the cam tracks 100 in such spacer member. As cocking ring 46 moves rearwardly, the engagement thereof with the engaging portions 75 on the strikers 44 causes such strikers to be retracted against the biases of the springs 72 to cock positions.

When the strikers 44 are in cock positions, the ledge portions 78 thereon are positioned rearwardly of sear 48, and the second chordal flats 76 are aligned with such sear. Whereby, sear 48 is free to be rotated by spring

96 to move the notches 90 out of alignment with the ledge portions 78 and thereby lock the strikers in the cock position.

When operating rod 16 is stopped in its rearward flight by a buffer mechanism (not shown) and is returned to normal forward position through the bias of operating rod spring 138, cocking ring 46 is returned to forward position by the counterrotation of feed rotor 18 and the cam tracks 100, leaving the strikers 44 releasably held by the engagement of the ledge portions 78 with sear 48. When operating rod 16 nears full forward position and bolt 28 is being locked in battery position, the prong portions 140 enter hole 150 of safety member 146 to cammingly engage cam block 154 and raise such safety member. As such safety member is raised, tab portion 152 thereon is withdrawn from in back of extension portion 128 of trigger 53 which when free is biased to normal forward position by spring 135. As a result, shelf portion 126 moves upwardly against the rear end of latch member 114 to pivot lip portion 120 thereon clear of sear release 50 which is then biased forwardly by spring 135 into recess 110 of sear 48 ready for actuating the sear when trigger 53 is actuated.

From the foregoing it should be clearly apparent that there is herein provided for salvo rifles having a plurality of barrels a novel and useful firing mechanism whereby all the barrels are fired together by a single trigger, the strikers for actuating the firing pin are cocked simultaneously and releasably held by a rotor sear, and the trigger for actuating the sear is safetied against actuation until the rifle is in battery with such firing mechanism being compact and simple in construction and positive in operation.

Although a particular embodiment of the invention has been described in detail herein, it is evident that many variations may be devised within the spirit and scope thereof and the following claims are intended to include such variations.

I claim:

1. For a rifle having a plurality of barrels, a bolt having a breech closure portion with a firing pin for each of the barrels and a feed rotor rotated responsive to the firing of the barrel, a firing mechanism including strikers spring-biased from a cock position into contact with the firing pins for actuation thereof to fire the rifle, cocking means simultaneously engageable with said strikers, cam means for converting rotation of the rotor to linear movement of said cocking means against said strikers for simultaneous retraction thereof to their cock positions, sear means for releasably holding said strikers in their cock positions, and means for actuating said sear means to release said strikers for simultaneous contact with the firing pins.

2. For a rifle having a plurality of barrels, a bolt having a breech closure portion with a firing pin for each of the barrels and a feed rotor rotated responsive to the firing of the barrel, a firing mechanism including strikers spring-biased from a cock position into contact with the firing pins for actuation thereof to fire the rifle, cocking means simultaneously engageable with said strikers, cam means for converting rotation of the rotor to linear movement of said cocking means against said strikers for simultaneous retraction thereof to their cock positions, a rotary sear disposed transverse to the rifle for rotatably securing said strikers in their cock positions, a trigger mounted for pivotal movement longitudinal to the rifle, and means for converting the pivotal movement of said trigger to rotary movement of said sear for releasing said strikers to strike the firing pins simultaneously.

3. For a rifle having a plurality of barrels, a reciprocable bolt having a breech closure portion with a firing pin for each of the barrels and a rotor for feeding cartridges to the barrels and for locking the bolt in a battery position, a firing mechanism including strikers spring-biased from a cocked position into contact with the firing pins for actuation thereof, cocking means mov-

ingly responsive to rotation of the rotor for retracting said strikers simultaneously to their cock positions, a rotary sear disposed transverse to the rifle for rotatably securing said strikers in their cock positions, a pivotally mounted trigger, means for converting pivotal movement of said trigger to rotary movement of said sear for releasing said strikers to contact the firing pins simultaneously, and safety means for blocking movement of said trigger until the bolt is locked in battery position.

4. For a rifle having a plurality of barrels, a reciprocable bolt having a breech closure portion with a firing pin for each of the barrels, an operating rod movably responsive to the firing of the rifle and a feed rotor longitudinally mounted in the firearm for delivering cartridges from a magazine into position for the bolt to chamber a cartridge simultaneously into each of the barrels and for locking the bolt in battery responsive to actuation of the operating rod, a firing mechanism including strikers mounted in the feed rotor for actuation against the firing pins by spring biasing means, a cocking ring engaged with the feed rotor for rotation therewith, means on said cocking ring for engaging said strikers simultaneously for retraction thereof, cam means for moving said cocking ring rearwardly responsive to rotation of the feed rotor for actuating said strikers simultaneously to cock position, a sear engaged with the feed rotor for rotation therewith and mounted therein for rotation respective thereto for rotatably securing said strikers in the cock position, a trigger mounted for pivotal movement longitudinal to the firearm, and means for converting pivotal movement of said trigger to rotary movement of said sear for releasing said strikers simultaneously to contact the firing pin.

5. The device of claim 4 wherein the means for converting pivotal movement of said trigger to rotary movement of said sear for releasing said strikers includes a sear release member mounted for rotational movement and for linear movement against said sear, a tooth portion extending radially from said sear release member, a recess in said sear for receiving said tooth portion, a side formed by said recess engageable by said tooth portion for transferring rotation of said sear release member to said sear for rotation thereof to release said strikers, a rectangular actuator member having angular displacement along the length thereof engaged by said trigger and slidably received by a mating orifice in said sear release member whereby retraction of said trigger rotates said sear release member to move said tooth portion against said side, mating cam portions on said tooth portion and in said recess for actuating said tooth portion from said recess during subsequent rotation of said sear by the feed rotor, a latch for releasably holding said sear release member in retracted position, and means on said trigger for moving said latch to release said sear release member when said trigger is in normal forward position.

6. For a rifle having a plurality of barrels, an operating rod movably responsive to the firing of the rifle, a bolt reciprocable by the operating rod and having a breech closure portion with a firing pin for each of the barrels and a feed rotor longitudinally mounted in the firearm for delivering cartridges from a magazine into position for the bolt to chamber a cartridge simultaneously into each of the barrels and for locking the bolt in battery responsive to actuation of the operating rod, a firing mechanism including strikers mounted in the feed rotor for actuation against the firing pins by spring biasing means, a cocking ring engaged with the feed rotor for rotation therewith, means for engaging said cocking ring to said strikers for retraction thereof, cam means for moving said cocking ring rearwardly responsive to rotation of the feed rotor for actuating said strikers simultaneously to their cock positions, a rotary sear disposed

transverse to the rifle for rotatably securing said strikers in their cock positions, a trigger mounted for pivotal movement longitudinal to the firearm, means for converting pivotal movement of said trigger to rotary movement of said sear for releasing said strikers simultaneously to contact the firing pin, safety means for blocking movement of said trigger after being actuated to fire the rifle, and cam means on the operating rod for moving said safety means to unblock said trigger as the operating rod rotates the feed rotor to lock the bolt in battery position.

7. For a rifle having a tubular receiver with a plurality of barrels extending therefrom, an operating rod reciprocable between a forward and a rearward position responsive to the firing of the rifle, a bolt reciprocable by the operating rod and having a breech closure portion with a firing pin for each of the barrels, a feed rotor longitudinally mounted in the front end of the receiver for rotation to deliver cartridges from a magazine into position for the bolt to chamber a cartridge simultaneously into each of the barrels and to lock the bolt in battery responsive to reciprocation of the operating rod and a reduced diameter portion on the rear end of the feed rotor forming an annular shoulder, a firing mechanism including strikers reciprocably mounted in the feed rotor for alignment with the firing pins when the feed rotor is rotated to lock the bolt and so that the rear portions thereof extend partially above the reduced diameter portion, spring means for biasing said strikers forwardly to strike the firing pin when released from a rearward cocked position, a cuplike housing having a lip portion longitudinally mounted in the receiver rearward of the feed rotor so that said lip portion is spaced from the annular shoulder, a sear rotatably mounted on the reduced diameter portion between said lip of said housing and the annular shoulder, a tang extending from the inside of said sear to be slidably received by a slot in the reduced diameter portion for limiting rotation of said sear between a lock and a release position, a spring mounted in said slot for biasing against said tang to rotate said sear to the locked position, a cocking ring slidably and rotatably mounted inside of said housing and having an inside diameter similar to the diameter of said reduced diameter portion so as to be slidable thereon, a first chordal flat provided on the rear portion of each of said strikers, clearance cuts in said cocking ring to permit slidable passage of the rear portions of said strikers where provided with said first chordal flat while engaging said cocking ring to the feed rotor for rotation therewith, engaging portions formed by said first chordal flats on each of said strikers engageable by the rear side of said cocking ring, a second chordal flat extending forwardly from each of said first chordal flats, forwardly facing ledge portions formed at the junction of said first chordal flats and said second chordal flats which are engageable with said sear when said strikers are in the cocked positions, and notches in said sear alignable with said ledge portions when said sear is in the release position to release said strikers for simultaneous actuation of said firing pin.

8. The device of claim 7 with a pivotal trigger, means for converting pivotal movement of said trigger to rotatable movement of said sear for releasing said strikers.

9. The device of claim 8 with a vertically-disposed T-slot in the base of said housing, a safety member mounted for slidable movement in said T-slot, a tab portion extending from said safety member for releasably blocking movement of said trigger after being actuated to fire the rifle, and a cam portion on the operating rod engageable with a cam block on said safety member for moving said tab portion to unblock said trigger when the operating rod is in the forward position.
